UNITED STATES PATENT OFFICE.

MILTON J. WILLIAMS, OF CHICAGO, ILLINOIS.

PULVERIZER.

939,776.

Specification of Letters Patent.

Patented Nov. 9, 1909.

Application filed February 16, 1909. Serial No. 478,218.

To all whom it may concern:

Be it known that I, MILTON J. WILLIAMS, a citizen of the United States, residing at Chicago, Illinois, have invented a certain 5 new and useful Improvement in Pulverizers, of which the following is a full, clear, and exact description, such as will enable others skilled in the art to which it appertains to make and use the same, reference being had 10 to the accompanying drawings, forming part of this specification, in which—

Figure 1 is a vertical sectional view through a pulverizer constructed according to my improvement. Fig. 2 is a horizontal, 15 fragmentary sectional view through the same. Fig. 3 is a detailed view of one of the guide bars through which the hammer supports pass.

This invention relates to a new and useful improvement in pulverizers of that type commercially known as the "Williams mills," characterized by the pivoted revolving hammers which act upon the material as it enters the machine at the hopper or 20 feed end thereof, crushing said material as it rests upon the bottom of the hopper, or breaker plate, as it is sometimes called, the material being further disintegrated or crushed by the hammers acting thereon as 25 the material is carried over the cage or grinding surface. The crushed material falls through the openings in the cage or grinding surface into a suitable receptacle located beneath the machine. The hammers 30 or beaters which revolve about the shaft, while made of a material whose resistance to wear is its essential quality, will, in time, wear away at their striking ends, and the farther these striking ends are removed from 35 the breaker plate and grinding surface, the less becomes the capacity of the machine.

It is the purpose of my present invention to provide means whereby these revolving hammers or beaters may be adjusted outwardly to take up this wear (or inwardly, if occasion requires, as when a new cage is introduced to replace a worn one), said means consisting of inclined rods which are movable longitudinally the shaft for effecting simultaneous and uniform adjustment of all of the hammers or beaters inwardly and outwardly.

In the drawings, 1 indicates the casing, 2 the breaker plate, 3 the grinding surface or cage, and 4 the cover of the machine, which may or may not be hung, as desired.

5 is a shaft mounted in bearings in the side frame of the machine driven in any suitable manner.

6 are disks in the form of head castings fixed to shaft 5.

7 are the head pieces of a frame, said frame consisting of said head pieces and inclined rods 8 connecting them. To one of these head pieces are secured threaded rods 9 passing through one of the disks 6 and also through a plate 10 secured to the disks 6, on each side of which plate 10 are arranged nuts 11 on said rods 9.

12 indicates bars whose ends are supported by the disks 6, said bars being provided with radially disposed openings in which are slidingly mounted hammer supports 13. In the outer ends of these hammer supports are pivot bolts 14 on which the hammers 15 are pivoted. The inner ends of the hammer supports 13 are provided with openings through which the inclined rods 8 pass.

In operation, when the striking ends of the hammers wear, the nuts on the rods 9 are adjusted so as to move the head pieces 7 and the inclined rods 8 longitudinally the shaft in a direction tending to force the hammer supports 13 outwardly. In this way the wear of the hammers is taken up.

When it is desired to put in a new cage, the frame containing the inclined rods is moved in an opposite direction so as to positively withdraw the hammer supports inwardly toward the shaft.

I am aware that minor changes in the construction, arrangement and combination of the several parts of my device can be made and substituted for those herein shown and described without in the least departing from the nature and principle of my invention.

In using the expression "disks" in the foregoing specification and in the following claims, I wish to be understood as not confining myself to circular disks, as the parts which perform the functions of the supporting disks described and claimed could be in the shape of spider-arms, or other forms, metal being cut away at various places, 105 where it was not needed, to lighten the machine.

Having thus described my invention, what I claim is:

1. In a pulverizer, the combination with a 110 casing, of a shaft, slotted hammer supporting bars carried by the shaft, hammer sup-

ports arranged to slide through the slotted bars, hammers mounted between the outer ends of said supports, and means coöperating with the inner ends of said supports to move them and their carried hammers outwardly.

2. In a pulverizer, a casing, a shaft journaled therein, hammer supports mounted to move radially relative to said shaft, hammers pivotally mounted on the outer ends of the hammer supports, and adjustable means arranged to slide on the shaft between the hammer supports and engaging the inner ends of all of the radially moving hammer supports for positively adjusting said hammer supports inwardly and outwardly.

3. In a pulverizer, the combination with a shaft, disks carried thereby, guide bars carried by said disks, hammer supports arranged to slide through said bars, hammers pivotally carried by said supports and a frame movable longitudinally the shaft, said frame having inclined rods engaging said hammer supports.

25 4. In a pulverizer, the combination with a casing, a shaft mounted in said casing, hammer supports movable radially with respect to said shaft, hammers pivotally carried by

said supports, inclined rods passing through openings in the inner ends of said hammer supports, means for moving said rods longitudinally relative to said shaft, and means whereby the rod-moving means is locked after movement.

5. In a pulverizer, a casing, a shaft journaled therein, a series of slotted bars carried by the shaft, hammer supports carried by the slotted bars and arranged to move radially relative to the shaft, revolving hammers pivotally carried by the outer ends of the hammer supports, there being openings formed in the inner ends of the hammer supports, inclined rods passing through said openings, disks arranged to slide upon the shaft and engaging the ends of the inclined rods, and adjustable means engaging one of the disks for shifting the same and the inclined rods.

In testimony whereof I hereunto affix my signature in the presence of two witnesses, this 8th day of February, 1909.

MILTON J. WILLIAMS.

Witnesses:

WILLIS MELVILLE,
REINHOLD E. WINTER.
